UNITED STATES PATENT OFFICE.

ADELBERT AMES, JR., OF TEWKSBURY, MASSACHUSETTS

PROJECTION APPARATUS.

1,263,016.

Specification of Letters Patent. Patented Apr. 16, 1918.

Application filed June 6, 1916. Serial No. 102,087.

To all whom it may concern:

Be it known that I, ADELBERT AMES, Jr., a citizen of the United States, and resident of Tewksbury, in the county of Middlesex and 5 State of Massachusetts, have invented new and useful Improvements in Projection Apparatus, of which the following is a specification.

This invention relates to light projection 10 apparatus designed to project a sharply defined, concentrated beam of light a considerable distance. More particularly the invention relates to a headlight for use on automobiles and the like adapted to illuminate 15 the roadway far in advance of the vehicle without producing upward glare, that is, without projecting substantially any light above a horizontal plane passing through the region of the light source, and at the 20 same time adapted to produce distributed illumination for relatively short and intermediate distances along the roadway.

In my prior applications Serial No. 72,504 and Serial No. 72,505, both filed January 17, 25 1916, and Serial No. 102,086, filed June 6, 1916, I have disclosed light projection apparatus comprising a paraboloidal or other concave reflector, a light source in the region of the focus of the reflector and a spherical 30 or other auxiliary reflector for reflecting to said paraboloidal reflector the light radiating from the source in certain directions, whereby all or substantially all the light emanating from the source may be projected 35 in and below a horizontal direction.

This invention comprises novel construction and arrangement of parts in apparatus of this character and the particular embodiment of the invention illustrated in the 40 drawings comprises a substantially paraboloidal reflector positioned below a horizontal plane with its axis in the said plane and a deflector in the form of a substantially spherical reflector positioned above said 45 plane with its center in the region of the focus of said paraboloidal reflector.

For illuminating the roadway in front of an automobile or other vehicle, for example, it is desirable to produce a beam of light 50 sharply defined by a horizontal plane passing through the region of the light source in order to avoid upward glare which would tend to blind persons meeting the vehicle. The beam of light should have a high degree 55 of concentration immediately below the horizontal plane to illuminate the roadway.

a considerable distance in advance of the vehicle and it should have a comparatively low degree of concentration throughout its lower portion to produce a distributed illumination over near and intermediate portions of the roadway.

As fully explained in my prior applications, above referred to my improved projector of the general type described produces 60 the desired distribution of light and at the same time eliminates upward glare. The desired distribution is preferably obtained by positioning the center of the upper spherical reflector rearwardly or upwardly or 65 both rearwardly and upwardly of the focus of the lower reflector and by placing the light source substantially between the said center and the said focus. The upward glare is preferably eliminated either by relatively 70 positioning the light source, the center of the upper reflector and the focus of the lower reflector, or by providing means adjacent the horizontal plane between the two reflectors to deflect or absorb the light which 75 would otherwise be projected in an upward direction, or by employing both of these expedients, as fully described in the applications above referred to.

However, it is at times desirable to vary 80 the distribution of the light throughout the aforesaid beam and even to vary the relative position of the beam to meet the requirements of different conditions, different drivers, different headlight laws, etc. To 85 this end I provide means to adjust the upper reflector relative to the lower reflector and to adjust the light source relative to both reflectors, and while I do not desire to limit myself to the particular adjustments disclosed I have found that suitable adjustments comprise means for moving the upper reflector parallel to the axis of the lower reflector and means for vertically moving the lamp relative to both reflectors.

Another object of the invention is to provide a headlight which utilizes all the light radiating from the light source to produce a beam of light of the character described and which at the same time is much lighter and 90 occupies less space, both vertically and horizontally, than the ordinary paraboloidal projector. Still another object of the invention is to utilize the space ordinarily occupied by the upper half of the projector in which to 95 mount the main light source and also an auxiliary light source.

Other objects of the invention will be apparent from the following description and the accompanying drawings, in which—

Figure 1 is a side view of one embodiment 5 of my invention showing a portion in section;

Fig. 2 is a front elevation of the embodiment shown in Fig. 1;

Fig. 3 is a plan view of a modified embodiment 10 of my invention showing the top cover, light sources and electrical connections removed; and

Fig. 4 is a vertical axial section through the modified embodiment shown in Fig. 3.

In the particular embodiments of my invention illustrated in the drawings the apparatus comprises a substantially paraboloidal reflector P positioned below a horizontal plane containing the axis thereof, a transparent front cover G, a deflector in the 20 form of a spherical reflector S positioned above the said horizontal plane with its center o above and behind the focus f of the paraboloidal reflector, a lamp L positioned with its light source between the center o and the focus f, an auxiliary lamp A and a casing C over the top of the apparatus.

The paraboloidal reflector P comprises substantially the lower half of an ordinary projector, and over the top thereof is provided 30 a flat cover plate 1 welded or otherwise suitably secured thereto around its edge 2. The front edge of the plate 1 is turned up to form a flange 3 which lies in the same vertical plane with the flange 4 formed around the front periphery of the paraboloidal reflector P. The glass cover G is held in place between two packing washers 5 and 6 by means of a flanged annular ring 7 secured to the flanges 3 and 4 by fastening means 8.

The spherical reflector S comprises a substantially hemispherical surface having flat horizontal members 9 for securing it in place. The lamp L is preferably mounted in a cylindrical extension 11 surrounding an 45 opening 12 in the top of the spherical surface of the reflector, and the lamp is preferably arranged to be vertically adjustable in the cylindrical member 11, a set-screw 10 being provided to hold the lamp in adjusted 50 position. The spherical reflector S is preferably flared outwardly around its rear lower edge, as shown at 13, and is also preferably curved inwardly around its front lower edge, as shown at 14, to prevent upward glare which might otherwise result 65 from the causes fully described in my aforesaid applications. The light source is preferably positioned above the focus f of the lower reflector P and for this reason means 60 to prevent upward glare from the rear upper portion of the lower reflector, such as described in application Serial No. 102,086 is unnecessary.

Plate 1, substantially covering the lower 65 reflector P, extends rearwardly as shown at

16, and the extension 16 is provided with an opening 17 having a depending flange 18 arranged to connect with the tubular conduit 19, which is secured thereto by means of two nuts fastened to the upper end of the conduit. The depending flange 17 is preferably filled with pitch or other material 20 to make the casing air tight at this point. The flat member 1 is provided with an opening 15 whereby the lamp L may extend therebelow, and whereby light may pass from the spherical reflector to the paraboloidal reflector. Screws 23 pass through slots 24 and are threaded into the plate 1, whereby the spherical reflector may be axially adjusted 30 relative to the paraboloidal reflector. Guides 26 mounted on the plate 1 are provided at the ends of the members 9 to prevent angular displacement of the spherical reflector as it is adjusted rearwardly and forwardly. 35

In the embodiment of the invention shown in Figs. 1 and 2, the auxiliary source of light A is mounted in a cylindrical extension 27 secured to the plate 1 with the light source extending upwardly through a circular opening 28 in the casing C, which is recessed as shown to afford space for the lamp in front of the vertical portion 29. The glass dome 31 resting on the extension 27 is provided to inclose the auxiliary light 90 source. The dome is held in position by means of a nut 33 having an in-turned flange co-operating with the external flange on the lower periphery of the dome, packing washers 34 being inserted above and below the glass flange. In this arrangement the auxiliary source of light is visible both from in front and from the sides of the apparatus. The vertical portion 29, may, if desired, be polished in order to reflect the light incident 105 thereto.

In the embodiment shown in Figs. 3 and 4 the auxiliary source of light A' is mounted in a cylindrical member 27 secured to the plate 1 as in Figs. 1 and 2, but the lamp is inverted so that the light source is positioned slightly below the axis of the paraboloidal reflector P, somewhat in front of the focus of the reflector. With this arrangement, the light from the auxiliary signal lamp is in part reflected from the paraboloidal reflector and in part radiates directly through the front cover G, but owing to the fact that the auxiliary source is displaced from the focus of the paraboloidal reflector, it does not produce concentrated light, being provided merely as a signal light and not as a source of illumination. The casing C' of this embodiment completely incloses the auxiliary lamp as well as the other parts as in Figs. 1 110 and 2, and in each modification the cover is secured to the horizontal plate 1 by means of screws 42.

In Fig. 4 is shown one suitable means of mounting either form of my improved ap- 115

paratus on a member 43 which, for example, may be a mudguard of an automobile. The mounting means comprises a member 44 having substantially the same contour as the member 43 and having an up-turned flange 46 at its forward edge which may be secured to the flange 4 of the reflector P. At its rear end member 44 may be connected to the plate member 16 by means of a turnbuckle 47 pivoted at its two ends to lugs on members 16 and 44 respectively. The conduit 19, arranged to house the electrical connections, projects through an opening 45 in member 44.

15 Owing to the fact that the projector P comprises only substantially one-half of the ordinary paraboloidal reflector, and yet projects all the light radiating from the light source, less vertical space is occupied by my apparatus than by the ordinary projector, notwithstanding the fact that the lamps and casing therefor project above the projector a certain limited distance. And owing to the fact that the lamps are mounted above the projector, instead of at the rear thereof as is ordinarily the practice, the apparatus occupies less space horizontally than does the ordinary type of reflector. The front glass cover is only half a circle and therefore 30 lighter than the ordinary glass cover, and a second shell surrounding and supporting the reflector shell is unnecessary owing to the reduced size and novel arrangement of parts. Thus, owing to its reduced size and reduced 35 weight, the apparatus may be employed in otherwise prohibitive places.

Furthermore, access to the lamps and other interior parts can be had by removing the cover C without removing the glass front 40 cover and the latter may be permanently secured to the reflector in an air tight manner by unusually light weight means. By employing the cover C as the detachable portion to permit access to the interior of the 45 lamp a hermetic seal may be more readily maintained inasmuch as the cover is metallic and can be tightly bolted to the plate 1. Furthermore, when the top cover is removed, the horizontal plate 1 serves to prevent contact with the polished surface of the reflector which would tend to cause tarnishment.

It is to be understood that the words horizontal, vertical, upward, downward, etc., 55 are used throughout the specification and claims merely for convenience in referring to relative locations and directions, and that my invention is not limited to headlights employed solely in the position herein described. On the contrary, the invention is applicable wherever it is desired to project a beam of light sharply defined on at least one side. I contemplate, for example, applying my invention to searchlights employed to illuminate buildings and the like.

In reciting that the deflector is detachable or movable with relation to the reflector I intend to include a pivotal movement between the two parts, the insertion or removal of the light source without disturbing the transparent front cover also being effected in this way, whereas with the deflector integrally or otherwise permanently secured to the reflector, the deflector is not only not adjustable relatively to the reflector but the light source is only accessible from the front of the apparatus for adjustment and replacement.

While I have described in detail certain specific shapes and sizes of parts, certain 80 relative positions of parts, etc., extensive variations of these factors obviously are included within the scope of the appended claims.

I claim:

1. Projection apparatus comprising a light source, a substantially paraboloidal reflector, a substantially spherical deflector mounted on the reflector, the light source being adjustably mounted on the deflector 90 so that its position with respect to the deflector may be varied, and means whereby the deflector may be adjusted along the axis of the reflector.

2. Projection apparatus comprising a 95 substantially paraboloidal reflector, a substantially spherical deflector positioned with its center in the region of the focus of the reflector, and a light source in said region, the deflector being mounted for adjustment in one direction and the light source being mounted for adjustment in a direction orientated with respect to the first direction.

3. Projection apparatus comprising a 105 substantially paraboloidal reflector, a substantially spherical deflector mounted for adjustment along the axis of the reflector, and a light source mounted for adjustment radially with respect to the said axis. 110

4. Projection apparatus comprising a light source, a concave reflector positioned with its axis horizontal and with its focus in the region of said light source, a substantially spherical reflector positioned 115 above said concave reflector with its center in the region of said light source to reflect light to said concave reflector, and means whereby the light source may be adjusted vertically and horizontally with relation to 120 the focus of the concave reflector.

5. Projection apparatus comprising a light source, a concave reflector having a focus in the region of said light source, said reflector being positioned at least in part 125 below a horizontal plane passing through the region of said light source, a substantially spherical reflector positioned above said light source with its center in the region thereof, means for horizontally adjust-

ing the spherical reflector, and means for adjusting the light source upwardly and downwardly.

6. Projection apparatus comprising a light source, a concave reflector having a focus in the region of said light source, said reflector being positioned at least in part below a horizontal plane passing through the region of said light source, and a substantially hemispherical reflector positioned above said light source with its center rearwardly of said focus, said light source being positioned substantially between said focus and said center.

15. 7. Projection apparatus comprising a light source, a concave reflector having a focus in the region of said light source, said reflector being positioned at least in part below a horizontal plane passing through 20 the region of said light source, and a substantially hemispherical reflector positioned above said light source with its center in the region thereof, said hemispherical reflector being flared out near a portion of its periphery.

30. 8. Projection apparatus comprising a light source, a concave reflector having a focus in the region of said light source, said reflector being positioned at least in part below a horizontal plane passing through the region of said light source, and a substantially hemispherical reflector positioned above said light source with its center in the region thereof, said hemispherical reflector being curved inwardly at and near 35 a portion of its periphery.

40. 9. Projection apparatus comprising a light source, a concave reflector having a focus in the region of said light source, said reflector being positioned at least in part below a horizontal plane passing through the region of said light source, a substantially hemispherical reflector positioned above said light source with its center in the 45 region thereof, and means in the region of said horizontal plane to prevent light being reflected to said concave reflector in such a manner as to be projected above said horizontal plane.

50. 10. Projection apparatus comprising a concave reflector formed by approximately half a revolution of substantially a conic section, a substantially hemispherical reflector positioned with its center in the region of the focus of said concave reflector, the hemispherical reflector having an aperture in the region of the center thereof, and means for mounting a lamp in said aperture with its light source disposed in the 55 region of the focus.

60. 11. Projection apparatus comprising a concave reflector formed by approximately half a revolution of substantially a conic section, said reflector having an edge substantially in 65 a plane parallel to the axis thereof, a member

attached to the edge of said reflector, a portion of which extends over the edge thereof, means surrounding an opening in said extending portion of said member, means for hermetically sealing said opening, a transparent front cover, means to hermetically seal said front cover on said reflector, a metallic cover for said reflector and means for hermetically sealing said cover to said member.

75. 12. Projection apparatus comprising a substantially semi-paraboloidal reflector, a substantially semi-spherical deflector mounted on the reflector with its center in the region of the focus of the reflector for deflecting light to the reflector, a light source mounted on the deflector in said region, means whereby the deflector may be adjusted with respect to the reflector, and means whereby the light source may be adjusted with respect to the deflector.

80. 13. Projection apparatus comprising a light source, a concave reflector having a focus in the region of said light source, said reflector being positioned at least in part below a horizontal plane passing through the focus thereof, and a substantially spherical reflector positioned above said light source with its center in the region of said source, the spherical reflector extending 95 down to said plane in such manner and the light source being positioned above said plane in such manner that a concentrated beam of light sharply defined on its upper side may be projected horizontally.

100. 14. Projection apparatus comprising a concave reflector having the shape formed by cutting away a portion thereof lying on one side of the axis of the reflector, a light source at the focus of the reflector, a deflector for deflecting light from the source to the reflector, an auxiliary light source, and means for mounting the deflector and auxiliary source substantially in the space which said portion of the reflector would 105 occupy, the deflector being movable relatively to the reflector.

110. 15. Projection apparatus comprising a concave reflector having the shape formed by cutting away a portion thereof lying on one side of the axis of the reflector, a light source at the focus of the reflector, an auxiliary light source, means for mounting the light sources substantially in the space which said portion of the reflector would 115 occupy, and a casing for the light sources arranged so that the auxiliary source projects outwardly through the casing in such manner that it is visible both laterally and forwardly.

125. 16. Projection apparatus comprising a concave reflector having the shape formed by cutting away substantially the portion thereof lying on one side of a plane containing the axis of the reflector, a main 130

- light source at the focus of the reflector, a deflector for deflecting light from the source to the reflector, an auxiliary light source in front of the main light source, means for mounting the deflector and light sources in the space which said portion of the deflector would occupy, and a casing for the deflector and main light source, the casing shielding the auxiliary light source 5 only on the rear whereby the source is visible both laterally and forwardly.
17. Projection apparatus comprising a concave reflector having the shape formed by cutting away a portion thereof lying on one side of the axis of the reflector, a main light source at the focus of the reflector, an auxiliary light source, means for mounting the light sources in the space which said portion of the reflector would occupy, and 20 a casing for the light sources, the casing having an opening through which the auxiliary light source projects.
18. Projection apparatus comprising a concave reflector having the shape formed by cutting away a portion thereof lying on one side of a plane containing the axis of the reflector, a main light source at the focus of the reflector, an auxiliary light source, means for mounting the light sources in the space which said portion of the reflector would occupy, a casing for the light sources, the casing having an opening through which the auxiliary light source projects, and a transparent dome around the auxiliary 25 source.
19. Projection apparatus comprising a concave reflector having the shape formed by cutting away substantially the portion thereof lying on one side of a plane passing through the region of the focus of the reflector, a member attached to the reflector substantially in said plane, a light source at said focus, a deflector for deflecting light to the reflector, and means for movably mounting the light source and deflector on said member substantially in the space which said portion of the reflector would occupy.
20. Projection apparatus comprising a concave reflector at least a portion of which
- is positioned on one side of a plane containing the axis of the reflector, a light source at the focus of the reflector, a deflector for deflecting light from the source to the reflector, and means for detachably 55 mounting the light source and deflector substantially within the space defined by a continuation of said portion of the reflector beyond said plane.
21. Light projection apparatus comprising a concave reflector having the shape formed by cutting away a portion thereof on one side of the axis of the reflector, a light source at the focus of the reflector, a transparent front cover for the reflector, a casing over the cut-away side of the reflector, and means for detachably mounting the casing so that it may be bodily removed, thereby to afford access to the interior of the apparatus without disturbing the front 70 cover.
22. Light projection apparatus comprising a concave reflector having the shape formed by cutting away a portion thereof on one side of the axis of the reflector, a transparent front cover for the reflector, a casing over the cut-away side of the reflector, means for detachably mounting the casing so that it may be bodily removed, thereby to afford access to the interior of the apparatus without disturbing the front cover, and means for mounting the light source in the casing.
23. Projection apparatus comprising a light source, a concave reflector, a detachable auxiliary reflector for reflecting light from the light source to the concave reflector, the auxiliary reflector having an aperture therein, and means for mounting the light source in said aperture.
24. Projection apparatus comprising a light source, a concave reflector, a detachable auxiliary reflector for reflecting light from the light source to the concave reflector, and means for mounting the light source on the auxiliary reflector.

Signed by me at Boston, Massachusetts,
this 23rd day of May, 1916.

ADELBERT AMES, JR.
